GARMENT HANGER

William T. Albrecht, Detroit, Mich.

Application January 8, 1945, Serial No. 571,742

5 Claims. (Cl. 223—96)

1

This invention relates to a garment hanger. More particularly it is an object of the invention to provide supplemental supports on a standard garment hanger to serve as pants hangers or skirt hangers and the like.

It is an object to provide a supplemental support which is adjustable but which in overall construction is extremely simple and inexpensive to manufacture.

Other objects and features of the invention relate to details of construction which will be evident in the following description and claims.

In the drawings:

Figures 1, 2 and 3 show three embodiments of the invention.

Figures 4 and 5 are sectional views taken on lines 4—4 and 5—5 of Figure 1.

Figure 6 is a sectional view taken on line 6—6 of Figure 2.

Figure 7 illustrates the manner in which a garment is frictionally engaged by a supplemental supporter.

Figure 8 is a sectional view on line 8—8 of Figure 3.

In Figure 1 a wire hanger of standard shape is shown with a suspension member 10 and garment supporting arms 11 and 12. These arms are each provided with a horizontal extension 13 which is received in a slot 14 in a horizontal cross-bar or connecting means 15. Also received in the slot is a relatively thin panel 16 which is supported by the connecting bar 15 below the hanger. Each end of the bar 15 is slotted at 17 and slidable in these slots is a spring member 20 which is shown best in Figure 4. The spring member 20 is formed in the shape of a U with bight portion 21 and legs 22 and 23. Each of the legs is turned inwardly to provide portions 24 and 25 having ends 26 and 27 which frictionally engage the lower portion of bar 15. The portions 24 and 25 also frictionally engage the panel 16 by reason of the inherent resilience of the spring material.

The spring members 22 are slidable in slots 17 to various positions along the bar 15 and may be used as shown in Figure 7 to clamp garments. If desired, the springs 22 may be used without the panel 16 so that the members 24 and 25 will operate to hold articles between their facing surfaces.

In Figure 2 a slightly different hanger construction is shown with a suspension member 30 hooked around a single panel 31 cut out in the shape of a coat hanger and slotted at 32 and 33 to receive the spring clips 22.

In Figure 3 another modification is shown.

2

The hanger here illustrated is composed of the suspension member 30 wrapped around a top connecting bar and garment support 40, each end of which is held in a slotted vertical piece 41.

5 The lower ends of the pieces 41 are connected by a flat panel 42 slotted at 43 and 44 for the retaining springs 22. The operation of the hanger shown in Figures 2 and 3 is the same as described in connection with Figure 1. The particular embodiment preferred depends on the material available for manufacture.

It will be understood that the device may be made of numerous materials. The flat portions may be made of ply wood or of sheet aluminum which is being produced now in large quantities. Sheet aluminum can be used to replace parts 15 and 16 shown in Figure 1 and the top edge rolled to receive projections 13 of the members 11 and 12.

20 I claim:

1. A garment hanger comprising a suspension member, a horizontal cross bar, shoulder supporting arms comprising wires leading from the suspension means to a recess within the ends of the cross bar, slots in each end of said cross bar, closed by said wires, and clamping means at each end of said bar, retained by and slidable in said slots having portions arranged to bear against said bar to engage garments and the like.

25 2. A garment hanger comprising a suspension member, a horizontal cross bar, shoulder supporting arms comprising wires leading from the suspension means to a recess within the ends of the cross bar, slots in each end of said cross bar, closed by said wires, and clamping means at each end of said bar comprising a U-shaped double-leg member, the bight of which is retained and slidable in said slot, the legs of which are urged together by the resilience thereof.

30 3. A garment hanger comprising a suspension member, a horizontal cross bar, shoulder supporting arms comprising wires leading from the suspension means to a recess within the ends of the cross bar, slots in each end of said cross bar, closed by said wires, and clamping means at each end of said bar comprising a U-shaped double-leg member, the bight of which is retained and slidable in said slot, the legs of which are urged together by the resilience thereof, and a panel supported by said bar between said legs to serve as a clamping surface.

45 4. A garment hanger comprising, a garment support having side members extending outwardly and angularly downwardly and adapted to receive and hold a garment in suspended man-

ner, a transverse member supported by the outer portions of the side members, said transverse member being disposed in a position spaced from the garment support, said transverse member including a lower portion of strip-like construction extending lengthwise of the transverse member and yieldable means supported by the transverse member and having an engaging element disposed adjacent one side of the strip-like portion, the engaging element being adapted to grip an article of clothing disposed between the strip-like portion and the engaging element.

5. A garment hanger comprising, a garment support having side members extending outwardly and angularly downwardly and adapted to receive and hold a garment in suspended manner, a transverse member supported by the outer portions of the side members, said transverse member being disposed in a position spaced from the garment support, said transverse member in-

cluding a portion of strip-like construction extending lengthwise of the transverse member, spring means of inverted U-shape having the bight portion suspended from the transverse member, said spring means having the legs of the U fashioned to provide engaging elements on opposite sides of the strip-like portion, said engaging elements adapted to frictionally engage and grip an article of clothing disposed between the strip-like portion and the engaging element.
